CLAIM

The ornamental design for a puzzle toy, as shown and described.

DESCRIPTION

FIG. 1 is a front, left and bottom perspective view of a puzzle toy, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof shown in a used condition; and,

FIG. 10 is another perspective view thereof shown in a used condition.

The broken lines shown in the drawings depict environmental structure and form no part of the claimed design.

1 Claim, 10 Drawing Sheets
